UNITED STATES PATENT OFFICE.

MELLEN N. BRAY, OF BOSTON, MASSACHUSETTS.

DESIGN FOR A LACING-HOOK.

No. 39,201.

Specification for Design.

Patented March 17, 1908.

Application filed August 10, 1904. Serial No. 220,273. Term of patent 14 years.

To all whom it may concern:

Be it known that I, MELLEN N. BRAY, of Boston, county of Suffolk, and State of Massachusetts, have invented and produced a new, original, and ornamental Design for Lacing-Hooks, of which the following is a specification.

Figures 1 and 2 of the drawing are a perspective view and plan view respectively of a lacing hook embodying my design.

I claim:
The ornamental design for a lacing hook as shown.

MELLEN N. BRAY.
